UNITED STATES PATENT OFFICE.

JOHN E. LAFFIN, OF WENTWORTH LOCATION, NEW HAMPSHIRE.

BARREL-JACK.

SPECIFICATION forming part of Letters Patent No. 783,699, dated February 28, 1905.

Application filed May 3, 1904. Serial No. 206,115.

To all whom it may concern:

Be it known that I, JOHN E. LAFFIN, of Wentworth Location, in the county of Coos and State of New Hampshire, have invented a new and Improved Barrel-Jack, of which the following is a full, clear, and exact description.

This invention relates to a device to facilitate the handling of barrels or casks to elevate or lower them to any desired elevation, and it is also arranged to make the placing and removing of the barrel an easy operation.

The device is particularly adapted for holding casks in which things are kept on draft or on tap and is to be used more by merchants, who have to frequently move or replace the barrels.

The invention is illustrated in the accompanying drawings, in which—

Figure 1 is a side view of the barrel-jack, and Fig. 2 is a section on line 2 2 in Fig. 1.

The construction of the jack embodies a pair of stringers 10, having on one end an inclined surface 10^a and being provided with the casters 11 to allow the shifting of the jack. On the end of the stringers opposed to the inclined end are arranged the uprights 12, having a cross-piece 13, into which is journaled a threaded shaft 14, the other end of the shaft being journaled in the bearing 15. This shaft 14 is threaded its entire length and is provided at its top with a miter worm-gear 17 on the shaft 18. A crank 19 provides means for turning the whole mechanism.

A pair of stringers 20 are arranged in the sleeves 21, that embrace the uprights 12, supplemental sleeves 22 and bolts 23 serving to stiffen the stringers 20 and assisting them in maintaining the load. The cross-bar 24, connecting the sleeves 21, is provided with a nut 40 25, through which passes the threaded rod 14, the rotation of the rod thereby affecting the elevation of the stringers 20. Slight depressions 26 may be made in all the stringers to prevent the rolling of the barrel or cask after it is in place, or the usual stops might be employed. The ends of the stringers 20 have inclined faces 27, and when the stringers 20 are lowered to rest on the stringers 10 the inclined faces 10^a and 27 form a ready means for the handling of a barrel or allow its easy roll-

ing up onto the stringers 20. Then by rotation of the handle 19 through the mechanism hereinbefore described the stringers 20 can be raised up to any desired height, and, if desired, an additional cask can be placed on the stringers 10. In this way a storekeeper could easily handle heavy barrels that contain liquids to be kept on tap without much trouble, and the casters on the bottom of the device provide a ready means for shifting the whole apparatus to any convenient part of the establishment.

It will be understood that the upper stringers 20 might be offset, so as to fold down inside or outside of the lower stringers 10 instead of settling down upon them. This would allow their also acting as brakes when in their folded position to prevent any rolling of the jack.

It will be seen that the connected base-stringers 10 form a secure base for the device, that the connected stringers 20 form a convenient platform, and that the parts 22 and 23 securely brace the platform.

Having thus fully described my invention, I claim as new and desire to secure by Letters Patent—

1. A barrel-jack comprising a base having one end inclined, a pair of standards rising from the base, a movable platform arranged to slide vertically on the standards, said platform having an inclined outer end, a sliding brace moving on the standards and connecting with the platform, and a gear mechanism to raise and lower the platform. 85

2. A barrel-jack comprising a base formed of a pair of stringers, a pair of standards rising from the said stringers, a platform formed of parallel stringers, said platform being mounted to slide on the standards, a cross-piece connecting the stringers of the platform, sleeves sliding on the standards and connecting by braces with the stringers of the platform, and a gear mechanism for raising and lowering the platform. 90
